UNITED STATES PATENT OFFICE.

JAMES B. LADD AND DAVID BAKER, OF PHILADELPHIA, PENNSYLVANIA.

FURNACE CONSTRUCTION.

1,027,738.

Specification of Letters Patent. Patented May 28, 1912.

Application filed March 29, 1911. Serial No. 617,604.

To all whom it may concern:

Be it known that we, JAMES B. LADD and DAVID BAKER, citizens of the United States, residing at Philadelphia, in the county of Philadelphia and State of Pennsylvania, have invented certain new and useful Improvements in Furnace Construction, of which the following is a specification, reference being had therein to the accompanying drawing.

This invention relates to the construction of blast or like furnaces and has reference more particularly to the part of the furnace above the boshes, that is the portion of the furnace extending usually from the supporting columns upwardly.

The objects of the invention are to reduce the thickness of the wall of this part of the furnace and to substitute for the usual massive fire brick wall, a thin wall structure of such form that it may be artificially cooled to resist the destructive effects of the heat within the furnace, will be capable of withstanding the severe strain to which in practical use it is subjected, and which may be substituted for the usual massive fire brick wall without the necessity of rebuilding the furnace.

With these ends in view our invention consists in a furnace in which a plurality of superposed rings comprising each a series of upright water-cooled plates, is arranged within an inclosing shell, and supported in an improved manner, as will be fully described in the specification and the novel features pointed out in the claims.

The invention consists also in the details of construction and combination of parts hereinafter described and claimed.

In the accompanying drawings:—Figure 1 is a vertical sectional elevation through the blast furnace having our invention embodied therein in one form. Fig. 2 is a horizontal section through the same on the line $a-a$ of Fig. 1. Fig. 3 is an elevation of one of the plates of which the wall is formed. Fig. 4 is a vertical sectional elevation through a furnace having our invention embodied therein in modified form.

Referring to the drawings: referring particularly to Figs. 1, 2 and 3:—1 represents the usual external shell of the furnace supported at its base by columns 2, and supporting at its upper end the furnace top, which shell surrounds and incloses the body of the furnace from the top of the boshes

upwardly. In applying our invention, we erect within the shell and some distance therefrom, a wall 4 consisting of a number of superposed belts or sections 5, 5^a, etc., in the present instance four sections, each comprising a series of upright segmental plates or staves 6—6, etc., assembled edge to edge to form a belt, the said sections thus formed being superposed one upon the other so as to constitute in effect a continuous circular wall extending upwardly from the boshes to the top of the furnace. The wall thus formed is lined with fire brick 7, and is supported at its base by the columns 2, the relation of the wall to the furnace shell being such that a continuous circumferential space is left between the two.

The plates or staves are preferably in the form of iron castings, shown more particularly in Fig. 3, having an inner curved face 6^a, an upper outwardly extending flange 6^b, and a lower outwardly extending foot 6^c, so that the plates of the several sections may be supported one upon the other, with the foot of the upper plate resting on the upper flange of the plate beneath, as shown in Fig. 1. The plates are further provided with transverse flanges or ribs 6^d on their faces, the function of which is to retain the brick lining in place and prevent the same from slipping downwardly in case the lining is burned through at any point. In order that the plates may be kept cool and the wall prevented from being burned or destroyed by the intense heat in the furnace, we propose to artificially cool the same. This is preferably effected by forming a passage 6^e through the plates for the circulation of cold water, the passage entering each plate at one side at its base and pursuing a circuitous course therethrough back and forth from one end to the other, leaving the plate at the opposite side, suitable inlet and discharge pipes 9 and 9^a being connected respectively with the inlet and outlet openings and extending outwardly through the surrounding furnace shell, as shown in Fig. 1.

With the plates assembled side by side, as shown, to form the circular sections or belts, and the latter superposed one upon the other, the feet of the upper plates will rest upon and be supported by the outwardly extending upper flanges on the plates beneath, and these abutting parts are firmly and rigidly connected together by

bolts 10 or by other suitable means. The feet of the lower series of plates will rest upon and be supported by a ring 11, which in turn receives support from the columns 5 2. By this construction there is formed a continuous practically integral wall structure extending from the columns upwardly to the top of the furnace and within the surrounding shell, and disconnected therefrom, the space between the wall and shell being preferably filled with a suitable material such as concrete, granulated slag or loam, and the like, as indicated at A in Fig. 1. In order that this wall structure will 15 properly withstand and resist the thrust against the plates, we propose to brace and strengthen the same by encircling bands 12-12, etc., surrounding the plates of the several sections and applied to the outer 20 edges of the horizontal ribs 13 projecting outwardly from the plates, the bands being fastened to the plates by horizontal bolts 14 passing through the bands and through the plates to the inner side.

25 In Fig. 4 we have shown a modified embodiment of our invention. In this case the form and construction of the individual plates and the general mode of assemblage is the same as the construction of Fig. 1, but in this modified embodiment, dependence is placed on the surrounding shell of the furnace for resisting the thrust against the plates. This is effected by supporting the plates at intervals from the shell, the 35 outwardly extending flanges on the upper ends of the plates being formed with downwardly extending lips 15 which interlock with flanged rings 16 fixed to the inner side of the furnace shell at intervals to correspond to the position of the flanges on the several sections of plates.

The first construction described, that is that illustrated in Fig. 1 where the plates are strengthened by encircling bands, is applicable to cases where the furnace shell itself does not possess sufficient strength to resist the thrust against the plates. The modified construction described, that is that illustrated in Fig. 4, is applicable to cases 45 where the furnace shell does possess the requisite strength to enable it to take the thrust of the plates.

The primary object of our invention is to substitute a thin wall as made up of the 55 artificially cooled fire brick lined plates or staves, for the usual massive wall of the furnace, and is especially designed to replace the massive wall when the latter becomes destroyed or cut away by the action 60 of the heat to such extent that it is rendered unfit for further use. This replacement involves a method which forms a part of

our invention, and in carrying out this method the damaged massive wall is first removed from within its inclosing shell and 65 the latter left intact, then the new composite wall is erected within the shell so as to leave a circumferential space between the new wall and the shell, and in some cases an additional step is carried out of filling in 70 the circumferential space with a filling material, such as cement and the like. By such replacement a great saving of time and expense is effected in the restoration of the damaged structure, and a new wall is produced very thin in comparison to the thickness of the former wall and of a character which may be artificially cooled so as to withstand without injurious effects the 75 severe heat within the furnace. 80

We have in the accompanying drawings illustrated certain embodiments of our invention which are deemed suitable for the realization of the objects to be attained, but it will be understood that the invention is 85 not limited to the particular and specific details shown, but may be modified within the skill of the mechanic provided the operation will be substantially as above described, and it will be further understood 90 that the invention is not limited to any particular form or construction of the parts except in so far as such limitations are specified in the claims.

Having thus described our invention, 95 what we claim is:—

1. In a furnace and in combination with an inclosing shell, a wall situated within the same and comprising a plurality of superposed rings or sections consisting each 100 of a series of upright water-cooled plates, said plates being supported at intervals, one above the other, by the inclosing shell.

2. In a furnace and in combination with an inclosing shell, a wall situated within the shell and comprising a plurality of superposed rings or sections, consisting each of 105 upright plates provided with outwardly extending flanges, said flanges being supported from the shell. 110

3. In a furnace and in combination with an inclosing shell, a wall situated within the shell and spaced therefrom, and comprising a plurality of superposed rings or sections, each consisting of a series of upright water-cooled plates, and strengthening bands encircling said plates. 115

In testimony whereof we have affixed our signatures in presence of two witnesses.

JAMES B. LADD.
DAVID BAKER.
